UNITED STATES PATENT OFFICE.

WILLIAM McCONWAY, JR., OF PITTSBURG, PENNSYLVANIA, ASSIGNOR
TO THE McCONWAY & TORLEY COMPANY, OF PITTSBURG, PENNSYLVANIA, A CORPORATION OF PENNSYLVANIA.

CAR-COUPLING.

SPECIFICATION forming part of Letters Patent No. 787,531, dated April 18, 1905.

Application filed December 3, 1904. Serial No. 235,361.

To all whom it may concern:

Be it known that I, WILLIAM McCONWAY, Jr., a citizen of the United States, residing at Pittsburgh, in the county of Allegheny and State of Pennsylvania, have invented certain new and useful Improvements in Car-Couplers; and I hereby declare the following to be a full, clear, and exact description of the same, reference being had to the accompanying drawings, in which—

Figure 1 is a plan view of a car-coupler embodying my invention, a portion of the coupler-head being broken away and one method of attaching the coupler to a car being illustrated, the draft-spring and followers of the attaching devices being omitted. Fig. 2 is a side elevation of the coupler and the draft-rigging devices shown in Fig. 1. Fig. 3 is an enlarged vertical section of the coupler-head, taken on the line 3 3, Fig. 1, the parts being in locked position. Fig. 4 is a view corresponding to Fig. 3, but showing the lock supported in unlocked position, while the knuckle is in closed position. Fig. 5 is an enlarged plan view of the knuckle member of the coupler. Fig. 6 is a side elevation of the knuckle looking in the direction of the arrow, Fig. 5.

Like symbols refer to like parts wherever they occur.

My invention relates particularly to the construction of that class of vertical-plane car-couplers in which the coupler-head is attached to the car-body by a plurality of stems or connecting-rods which are pivotally or otherwise flexibly attached to the coupler-head; but the same is also applicable to the usual construction of couplers employing a rigid shank whenever it is desirable to locate the knuckle-locking device on the knuckle side of the longitudinal axis of the shank.

In the construction of car-couplers having a plurality of stems or shanks, or, as they are commonly termed, "three-stem" couplers, it is desirable that the coupler-head shall be of small dimension in the direction of length of the car, as the length of air-brake hose is usually such that an excessive length of coupler-head is liable to pull the hose-couplings apart,

while if the air-brake hose be lengthened to compensate for an increased length of coupler-head then when not connected with the hose of another car such hose drags upon the track and is liable to be torn from its connection with the car. To maintain the desired length of coupler-head, while at the same time assuring a strong and efficient knuckle, I locate the knuckle-locking means to one side of the longitudinal axis of the coupler and on the knuckle side thereof, and so form the lugs or outer end of the knuckle and the tail or inner end of the knuckle that the angle between them facing the guard-arm side of the head is obtuse, the tail of the knuckle being provided with a spur or impact member, by means of which the knuckle is forced to a locked position by the impact of another coupler, and such a construction embodies one feature of my invention.

There are other minor features of invention residing in particular constructions and elemental combinations, all as will hereinafter more fully appear.

I will now proceed to describe my invention more fully, so that others skilled in the art to which it appertains may apply the same.

The manner here illustrated of connecting the type of coupler shown to the car-framing is well understood and therefore will not be described herein.

In the drawings chosen to illustrate my invention, the scope whereof is hereinafter pointed out in the claims, A is a coupler-head of the three-stem type, the same being preferably provided at suitable points with a jaw 1^a for the reception of the center stem and with laterally-located jaws 2¹ 2² for the reception of the side stems, the said center stem and side stems being flexibly attached to their respective jaws by pivot-pins or in other suitable manner.

The lock B, which is located to one side of the longitudinal axis of the head and on the knuckle side thereof, is preferably a vertically-sliding pin guided in its movements by apertures in the upper and lower walls of the coupler-head, the said lock, if desired, being

adapted to form a housing for certain devices herein shown but not specifically claimed. The lock B, for a purpose which will herein-after appear, is or may be provided with a notch or equivalent pocket 1^b and with a lug or projection 2^b below the latter, said notch and lug being preferably located adjacent to that part of the lock which abuts the knuckle when the parts are in a locked position.

- 10 1^c The knuckle D, which is pivotally attached to the coupler-head by the usual and well-known knuckle-pin C, is preferably so formed that the outer or lugs portion 1^d upon one side of the knuckle-pin hole 3^d and the inner 15 or tail portion 2^d upon the other side of such knuckle-pin hole form an obtuse angle facing toward the guard-arm side of the coupler-head, the tail of the knuckle 2^d when closed thus assuming a position in which it is adapted to be locked by the lock B and the knuckle-pin hole 3^d, being thereby enabled to be located at such a point that the strength of the knuckle is least impaired thereby.

Upon the locking side of the tail 2^d of the 20 knuckle D and located in advance of and somewhat nearer the knuckle-pin hole 3^d than is the locking face or abutment 4^d thereof in order to permit the proper operation of the lock B the said knuckle D is preferably provided with a laterally-extending spur or equivalent impact member 8^d, which when the knuckle is in an open position emerges through the opening in the face of the coupler-head and presents a curved face to receive the impact of 25 an opposing knuckle in a coupling operation, thus relieving the outer or lugs portion 1^d of the knuckle from undue wear of the opposing guard-arm and either supplementing the closing tendency of the knuckle due to the impact of such opposing guard-arm or supplanting such action accordingly as such laterally-extending impact member is arranged to emerge more or less from the said opening in the face of the coupler. The tail 2^d of the 30 knuckle D is also preferably provided upon its upper face with an inclined projection 5^d for actuating the lock-set and knuckle-opener member upon an opening movement of the knuckle and beyond said projection 5^d and 35 adjacent to the inner end of the said knuckle-tail with a lock-supporting shelf 6^d, the latter being preferably of substantially wedge form and extending from the locking-face or abutment 4^d of the locking portion of the knuckle-tail to or substantially to the end of the hook portion 7^d thereof.

Secured within the head in such manner as to permit the rotation of the knuckle D, but preferably pivoted therein in such manner as to 40 have a limited movement in any direction in the plane of its operation, is the lock-set and knuckle-opener member E, which is preferably formed with an enlarged eye through which passes the pivot-pin by means of which 45 the said member E is attached to the coupler-

head. The lock-set and knuckle-opener member E is provided with a detent member or finger 1^e, which is adapted to engage the lock-set notch 1^b of the lock B to support the latter in unlocked position and to engage the 70 knuckle-opener lug or projection 2^b of the said lock to open the knuckle, as will herein-after appear. Upon the member E and preferably located below the detent 1^e thereof is a depending lug or trip-finger 2^e, which upon 75 an opening movement of the knuckle D coacts with the inclined projection 5^d of the knuckle-tail to cause the withdrawal of the detent 1^e from supporting engagement with the lock D so that such detent 1^e have previously engaged 80 the lock-set notch 1^b in its supporting capacity.

Extending downwardly behind the tail of the knuckle is the knuckle-opener arm 3^e of the lock-set and knuckle-opener member E, said arm 3^e preferably resting when the parts 85 are in a locked position upon a supporting-abutment 3^a upon the floor of the coupler-head A, thus relieving the pivot-pin by which the member E is attached to the head from the weight of such member, and thereby permitting the said lock-set and knuckle - opener member E to readily fall or move into engagement with the lock-set notch 1^b of the lock B whenever the latter is raised sufficiently high.

The construction of the several parts being 90 substantially such as hereinbefore pointed out, the operation of the device in respect of the parts herein described will be as follows: Assuming the several parts to be in a locked position and the knuckle D to be restrained from rotation, an upward or unlocking movement of the lock B will cause the said lock B to assume a position in which the knuckle may be subsequently opened, the detent or lock-set finger 1^e of the lock-set and knuckle-opener member E entering the lock-set notch or pocket 1^b of the lock B, and the latter being thus supported in an unlocked position. The lock being thus supported in an unlocked position, an opening movement of the knuckle will cause the inclined projection 5^d to so contact with the trip-finger 2^e of the lock-set and knuckle-opener member E that the detent finger 1^e thereof is rotated out of the lock-set notch 1^b of the lock B, and the latter being 105 thus released from the supporting engagement of the said member E drops upon the lock-supporting shelf 6^d of the knuckle D, upon which it rides until dropped before the knuckle to lock the same when the said knuckle is subsequently brought to a locked position. The closing movement of the knuckle also serves to return the knuckle-opener arm 3^e of the lock-set and knuckle-opener member E to its position upon the 110 abutment 3^a of the coupler-head A. Should the knuckle be free to rotate when the lock B is brought to an unlocked position, a continuous pull upon said lock will cause the lug or projection 2^b, which lies below the notch 115

1^b of the lock B to engage the detent 1^c of the member E, which has previously moved into engagement with the said notch 1^b, and the knuckle-opener arm 3^e of the member E is 5 thus rotated to force the knuckle D outward by reason of the engagement of such knuckle-opener arm 3^e with the rear face of the knuckle-tail. When the pull upon the lock B is released, said lock seats itself upon the lock-supporting shelf 6^d of the knuckle, by which it is supported until the knuckle is returned to a locked position, the latter by such return to a locked position also restoring the knuckle-opener arm 3^e of the member E to its initial 15 position on the abutment 3^a of the coupler-head A.

By reason of the location of the locking devices upon the knuckle side of the coupler-head and the use of a knuckle having its portions on opposite sides of the knuckle-pin hole at an obtuse angle to each other it will be observed that the knuckle-pin may be so located that the combined lock-set and knuckle-opener member may operate through a comparatively small distance in opening the knuckle, with the consequent desirable decrease in the movement of the lock.

Having thus described my invention, what I claim, and desire to secure by Letters Patent, is—

1. In a car-coupler, the combination with a coupler-head, of a lock, a knuckle having a laterally-extending impact member upon the locking side of the tail thereof, and means operative by the lock for opening said knuckle, substantially as and for the purposes specified.

2. In a car-coupler, the combination with a coupler-head, of a lock located upon the knuckle side thereof, means operated by the lock for opening the knuckle, and a knuckle the lugs portion and the tail portion whereof form an obtuse angle facing the guard-arm side of the coupler-head, said knuckle having an impact member upon the tail thereof adapted to receive the impact of an opposing knuckle in a coupling operation, substantially as and for the purposes specified.

3. In a car-coupler having a plurality of stems, the combination with a coupler-head, of a lock located upon the knuckle side thereof, a knuckle, and means for opening said knuckle, substantially as and for the purposes specified.

4. In a car-coupler having a plurality of stems, the combination with a coupler-head, of a lock located upon the knuckle side of the coupler-head, a knuckle, and a lock-set and knuckle-opener member adapted to support

the lock in unlocked position and also to open the knuckle, substantially as and for the purposes specified.

5. In a car-coupler, the combination with a coupler-head, of a lock located upon the knuckle side thereof, a knuckle the lugs portion and the tail portion whereof form an obtuse angle facing the guard-arm side of the coupler-head, and a lock-set and a knuckle-opener member adapted to support the lock in unlocked position and also to open the knuckle, substantially as and for the purposes specified.

6. In a car-coupler, the combination with a coupler-head, of a lock located upon the knuckle side thereof, a knuckle the lugs portion and the tail portion whereof form an obtuse angle facing the guard-arm side of the coupler-head, said knuckle having an impact member upon the tail thereof, and a lock-set and knuckle-opener member adapted to support the lock in unlocked position and also to open the knuckle, substantially as and for the purposes specified.

7. A knuckle adapted for use with car-couplers having the lock located on the knuckle side of the coupler-head, said knuckle having a lugs portion and a tail portion, said tail portion being provided with a laterally-extending impact member and having an inclined projection adapted to actuate a lock-set member, substantially as and for the purposes specified.

8. In a car-coupler having a plurality of stems, the combination with a coupler-head, of a lock located upon the knuckle side thereof, a knuckle, and means automatically operative by an unlocking movement of the lock for supporting said lock in unlocked position while the knuckle is in closed position, substantially as and for the purposes specified.

9. In a car-coupler having a center stem and side stems, the combination with a coupler-head, of a knuckle having a laterally-projecting impact member upon the tail thereof, and a lock for said knuckle located upon the knuckle side of the coupler-head and interposed between the center stem and a side stem, substantially as and for the purposes specified.

In testimony whereof I affix my signature, in presence of two witnesses, this 2d day of December, 1904.

WILLIAM McCONWAY, JR.
